MEASURE

Filed Sept. 16, 1925

Inventor:

A. M. English,

By *H. S. Woodward*

Attorney

UNITED STATES PATENT OFFICE.

ANALDO M. ENGLISH, OF BROOKLINE, MASSACHUSETTS.

MEASURE.

Application filed September 16, 1925. Serial No. 56,783.

- The invention has for an object to embody a measuring device especially suited to the uses illustrated in my copending application, Ser. No. 19,721, filed March 31, 5 1925, for measuring appliances for package filling machines, although it may be used in other situations also. This application is in part a continuation of said prior application.
- 10 It is a particular object to arrange a construction which will be self contained within symmetrical limits and accessible readily for capacity adjustment without requiring elements that would interfere with the peculiar 15 operative mechanism shown in my said prior application. Also, it is very desirable in such a machine, and a further object, to provide means for adjusting the capacity of a receptacle of this character without requiring any element of the adjusting means to be located exteriorly of the receptacle. In this direction it is a particular object to enable the use of the simple structure including a bottom member having a wide 20 range of adjustment engaged revolubly in threads within the receptacle element, yet obviating necessity for exposure of these threads, at the same time that the elements are retained within moderate dimensional 25 limits. Thereby, fouling of the threads by coated products or other materials having an adhesive and gumming tendency is avoided; and also—which is of much importance—the stock handled is protected 30 from damage by the sharp edges of threads.
- Additional objects, advantages and features of invention may appear from the construction, arrangement and combination of parts as hereinafter described and shown in 35 the accompanying drawings, wherein
- Figure 1 is a side elevation of one embodiment of the invention;
- Figure 2 is a cross section thereof on an enlarged scale;
- 40 Figure 3 is a top view of the measure;
- Fig. 4 is a bottom view of the measure;
- Figure 5 is an elevation of the measure as it may be formed for hand manipulation.
- 45 There is illustrated a cup body 10, having in Figure 1 a stem 11 adapted to be
- connected with a mechanism for its operation, but as in Figure 5 it may be adapted for manual operation, and other adaptations will readily suggest themselves to those requiring such a device. The body 10 is of 55 cylindrical form, adapted to be cast in metal cylindrically, and having interior raised screw threads 12, extending for one-half the interior axial dimension of the cup. An integral bottom 13 is shown on the body 10, but 60 this may have a large opening therethrough, or may be omitted, if desired. The top edge 14 of the wall of the cup is rounded, and the exterior surfaces and the interior surfaces above the threads are smoothly 65 finished.
- Revoluble within the cup body 10 there is an adjustable inner cup 15 including a cylindrical wall 16 and bottom 17, the altitude of this cup being approximately one 70 half that of the interior of the cup body 10. Raised external threads 18 are formed on the cup 15, of the same size and pitch as those on the interior of the body 10, and the wall 16 is formed with a flare or round- 75 ed, outturned lip 19, finished to smoothly and slidably fit the wall of the body 10.
- The cup 15 is screwed into the body 10 and adjusted so that the space in the cup 15 and within the wall of the body 10 there- 80 so above will contain the desired quantity of stock. Where the bottom of the body 10 is left open a key-receiving means, as, a slot 20, may be formed in the bottom of the cup so that the latter may be rotated by a screw- 85 driver or other key-like implement.
- There is shown engaged through the bottom 16 a set screw 22, located opposite the stem 11 as close to the wall of the cylinder 10 as practicable, having a head disposed 90 below the bottom 13, and its inner end arranged to bear against the bottom 17 of the inner cup. This serves as a means to secure the cup 15 in adjusted positions by friction between the threads of the two 95 members of the measure.
- I claim:
- In a device of the character described, a measuring device comprising an outer cylinder, having threads on the interior thereof 100

at the inner part only, and an adjustable bottom having external threads screwed into the threaded part of said cylinder, said bottom having a wall portion set away from the wall of said cylinder and extending longitudinally beyond the threads on both cylinder and bottom, the extreme edge of said

wall being disposed in close relation to said receptacle beyond the threads on the bottom a distance substantially equal to the range 10 of adjustment of the bottom.

In testimony whereof I affix my signature.

ANALDO M. ENGLISH.
